UNITED STATES PATENT OFFICE.

WILLIAM HUMPHREY PERRIN, OF HARLEY TOWNSHIP, ONTARIO, CANADA.

SHOCKING ATTACHMENT FOR BINDERS.

No. 806,283.

Specification of Letters Patent.

Patented Dec. 5, 1905.

Application filed April 7, 1905. Serial No. 254,287.

To all whom it may concern:

Be it known that I, WILLIAM HUMPHREY PERRIN, of the township of Harley, in the district of Nipissing, Province of Ontario, Canada, have invented certain new and useful Improvements in Shocking Attachments for Binders, of which the following is a specification.

My invention relates to improvements in shocking attachments for binders; and the objects of my invention are to devise a mechanism which may be readily attached to any ordinary form of grain-binder and which will be operated by the mechanism of the binder in such a manner that the sheaves of grain as they are thrown from the binder will be caught and held by the shocking attachment until a given number of them have been collected, when they will all be dropped to the ground in an upright position, supporting each other in a shock or stook, further objects being to make my device extremely simple in operation and adjustable in its various mechanisms; and it consists, essentially, of a plurality of pivoted forms, each supported by two arms carried by an intermittently-revolving part, such revolving part being held on a substantially vertical shaft, which is supported from the frame of the binder by suitable means, means being further provided whereby a driving mechanism of the knotter of the binder will intermittently revolve the forks through determined distances, whereby as each sheaf is ejected from the binder a fork will be in such a position as to catch the sheaf and will then support it until all the forks have caught their respective sheaves, the device being provided with further means whereby a trip mechanism will then operate to release all the sheaves together and drop them to the ground in an upright position, the various details of the device being constructed and arranged as hereinafter more particularly described.

Figure 1 is a perspective view of the side portion of a grain-binder of any ordinary construction, showing the attachment in place. Fig. 2 is a detail perspective view of the revolving portion of the attachment which carries the forks. Fig. 3 is a sectional view of the revolving parts of the mechanism and the shaft upon which these parts revolve. Fig. 4 is a side view of the mechanism attached to the binder for throwing the sheaf out in the proper position to be caught by the forks. Fig. 5 is a plan view of the cam which oper-

ates the forks. Fig. 6 is a side view of the stationary and movable collars on the shaft. Fig. 7 shows a longitudinal view of the knotter-shaft *c*, showing the position of the arms *e* and *f* thereon. 60

In the drawings like characters of reference indicate corresponding parts in each figure.

Referring to Fig. 1, *a* is the table of the binder, down which the grain passes while it is being formed into the sheaf and tied by the knotting mechanism, partly shown at *b*. The details of this knotting mechanism need not be described here, as its construction is well-known to any one skilled in the art. It may, however, be mentioned that a shaft *c* is rotated in the direction indicated by the arrows in Figs. 1 and 4 by suitable means to operate the knotting mechanism. This shaft is journaled in a bearing formed in a strong casting *d*, which is secured to or formed integral with 70 the frame of the machine. 75

At or near the inner extremity of the shaft *c* an arm *e* is provided which in rotating engages the head ends of the sheaves and forces them first down the sloping table and finally 80 raises the heads of the sheaves with an upward throw at the moment when they are falling from the table.

A second arm *f* is secured to the shaft and rotates therewith. This arm is provided with 85 an extension *g*, which is pivotally secured to the main portion at *h*. The extension *g* has a projecting part *i*, which extends at an angle therefrom and is provided at its extremity with a roller *j*. This roller as the shaft rotates comes in contact with the surface of a cam *k*, this cam being secured to any suitable part of the binder, but preferably to a pair of rods 90 11, which are generally used as braces for the shaft *c*. As long as the roller *j* is in contact with the cam *k* it will be seen that the pivoted portion *g* of the arm *f* will be kept rigid, so that it will force the lower ends of the sheaves forward down the slope of the table *a*. At the moment when the sheaf is leaving the table, however, the roller *j* runs off the end of the cam, so that the arm *f* has no effect in forcing the lower portion of the sheaf any further, and the result is that the sheaf is thrown 95 off the table with the head end up and the stalk end down in a position ready to be caught by the mechanism to be described hereinafter. 100

Referring to Figs. 1, 2, and 3, it will be seen that I have provided a vertical shaft *m*, which is supported from the frame of the 110

binder by a suitable support *n*, which is clamped to the casting *d* or otherwise secured by any suitable means.

5 *oooo* are forks. Each of these forks is pivoted at its end to arms *p* and at a point intermediate of its ends to an arm *q*. The arms *p* are pivoted in proximity to their upper extremities by suitable means to projections *r*, extending outwardly from a rotatable block *s*, 10 which is carried by the shaft *m*. Rollers *t* are provided at or near the ends of the arms *p* and are adapted to engage a stationary cam *u*, which is secured to the upright shaft *m* rigidly by a pin *v* or other suitable means and 15 forms a support for the block *s*.

The form of the cam *u* is shown in Fig. 5, and the object thereof will be hereinafter described. The upper surface of the block *s* is provided with ratchet-teeth *w*, which correspond in number to the number of forks carried by the device. A ratchet-disk 2 is mounted on the shaft above the block *s* and is provided with teeth corresponding to the teeth *w* and is spring-held in engagement with the teeth *w* by suitable means, such as a spiral spring 3, which surrounds the shaft *m* and engages a collar 4. A projection 5 is formed on the ratchet-disk 2 and is suitably engaged by a driving-arm 6, the opposite end of which is secured to a pin or projection 7, extending outwardly from the rotating arm *e*.

The length of the throw of the arm 6 is so regulated as to move the ratchet-disk 2 through a portion of a revolution of a size depending 35 on the number of forks used on the device—that is to say, a quarter of a revolution if there are four forks or a sixth of a revolution if there are six forks. Consequently it will be seen that the block *s* will be rotated an 40 equal distance, but will always be rotated in the same direction, owing to the ratchet connection which it has with the disk 2. The effect will therefore be to cause the arms *p* and the arms *q* and the parts to which they are secured to rotate in the direction indicated by 45 the arrow in Fig. 2.

It may here be mentioned that the upper ends of the arms *q* are pivotally secured to projecting pieces 8, which are formed on a slidable collar 9. (Shown in detail in Fig. 6.) This collar has a downwardly-extending semicylindrical portion 10. A stationary collar 11 is provided on the shaft *m* below the collar 9 and is formed with an upwardly-extending 55 semicylindrical portion 12, corresponding in shape to the portion 10. A strong compression spiral spring 13 extends between the collar 11 and the under side of the collar 9, and it will be seen that as long as these two 60 collars are held apart on the shaft *m* the forks will be held approximately perpendicular to the arms *p* and *q*, or, in other words, in a position in which they would support a sheaf. If, however, the collar 9 through any means 65 were forced to slide down the shaft *m*, so that

the two semicylindrical portions 12 and 10 would overlap each other and together surround each one-half of the same portion of the shaft, or, in other words, would be on a level with each other, the result would be that 70 the forks would be tilted down into such a position that the sheaves would slide off their ends. This is what actually takes place in the machine, the operation being as follows:

At each stroke of the arm 6 one of the rollers *t* runs up on the projecting portion 14 of the stationary cam *u*, and thereby throws out the arm *p*, the fork secured thereto, and consequently the arm *q*, into such a position that the upper portion of the sheaf, which is at the 80 same time being thrown off the table *a*, will be caught by the fork as the roller falls back into its normal position down the steep portion 15 of the cam. It will here be explained that spiral springs 16 extend between the 85 arms *p* and suitable portions of the rotatable block *s* and are adapted to pull the arms back into their normal position as the rollers pass over the cam. The next stroke of the arm 6 rotates the forks, and thereby carries the sheaf 90 away from the front of the table and brings the next fork into position to catch the next sheaf in a similar manner. Immediately after the last fork has engaged its sheaf the two 95 semicylindrical portions 10 and 12 will come into the position in which the upper one can slide down on the shaft into the position shown in Fig. 6 without being prevented by the lower one. The weight of the four sheaves acting 100 on the forks and through the arms *q* will produce this result, and accordingly the sheaves will all be dropped to the ground in the upright position, so as to form a "stook" or "shock." Immediately the weight of the 105 grain is removed from the forks the strong spiral spring 13 will force the collar 9 up again into the position shown in Fig. 3, thereby causing the semicylindrical portion 10 to clear the similar portion 12 and enabling the 110 rotatable parts to continue to rotate as before at each stroke of the arm 6. The operation then continues so long as the binder continues to throw out the sheaves.

It will now be seen that I have devised an extremely simple and cheap attachment for 115 binders which with a very small additional amount of power will save the labor required in stooking the sheaves by hand. The device has the further advantage of being applicable to most of the ordinary forms of binders at 120 present in use with very slight changes and is simple and cheap in construction, so that any farmer can readily understand the method of assembling and adjusting its various parts.

It is to be understood that in practice I may 125 make certain variations in the details of construction of the device without departing from the spirit of my invention. I therefore do not wish to limit myself to the exact form of the device shown herein.

What I claim as my invention is—

1. In a shocking attachment for binders the combination with a plurality of forks, of means whereby each of said forks, is caused to catch 5 a sheaf as it is thrown from the binder and means whereby the said forks will be caused to drop their sheaves together in shocks or stooks as and for the purpose specified.
2. In a shocking attachment for binders the combination with a plurality of forks, of means 10 for suspending the same in proximity to the discharge-table of the binder, means for intermittently rotating said forks, means for causing each fork to catch and hold a sheaf as it comes into a predetermined position, and means for automatically causing all the forks 15 to drop their sheaves at the same time in such a manner as to form a stook or shock as and for the purpose specified.
3. In a shocking attachment for binders the combination with a plurality of forks, of means for suspending the same normally in an upwardly-slanting position in proximity to the discharge-table of the binder, means for intermittently rotating the forks, means for causing each fork to engage and suspend a sheaf as it passes the discharge-table and means for releasing the device for holding the forks in the upwardly-slanting position when all the 25 forks are loaded whereby the sheaves will be dropped from all the forks together and will form a shock or stook as and for the purpose specified.
4. In a shocking attachment for binders the combination with a plurality of forks of a substantially vertical shaft, means for supporting said shaft from the frame of the binder, collars rotatably mounted on the shaft, arms suspending the forks from said rotatable collars, 30 ratchet-teeth formed on one of the collars, a ratchet adapted to engage said ratchet-teeth, a connection extending between said ratchet and a suitable driving portion of the binding mechanism, whereby the forks are intermittently rotated, means for causing each fork as it comes into a predetermined position to catch a sheaf, and automatic means whereby the sheaves will all be dropped from the forks together in an upright position whereby a shock 35 or stook is formed as and for the purpose specified.
5. In combination a plurality of forks, pairs of arms supporting said forks normally in an upwardly - slanting position, a substantially vertical shaft, upper and lower rotatable collars carried by the shaft to which said arms are pivotally secured, a roller on the upper end of the outer arm of each pair, a stationary cam secured to the shaft and adapted to be engaged 40 by said rollers, means for rotating said arms and parts secured thereto intermittently through determined distances, whereby said cam will cause each pair of arms to swing outwardly as it comes in proximity to the binder and whereby said arm at the moment when a 45 sheaf is being discharged will swing inwardly whereby the fork will engage the sheaf, and means whereby the sheaves carried by all the forks will be simultaneously discharged as and for the purpose specified. 70
6. In combination a plurality of forks, pairs of arms carrying said forks normally in an upwardly - slanting position, a substantially vertical shaft, upper and lower rotatable collars, carried by said shaft to which said arms 75 are pivotally secured, means for rotating said collars and the parts secured thereto intermittently whereby the forks are brought successively into the position to catch a sheaf as it is discharged from the binder, a downwardly - extending semicylindrical portion formed on the lower rotatable collar, an upwardly-extending semicylindrical stationary portion formed on, or secured rigidly to, the shaft below the lower rotatable collar, a compression-spring extending between said lower rotatable collar and the stationary part secured to or formed on the shaft, as and for the purpose specified. 80
7. In a device of the class described the combination with the forks rotatably suspended and the means for causing the same to engage and discharge the sheaves as they are thrown from the binder, of the binder-knotter mechanism including a rotatable shaft, an arm 90 secured at or near the end of said shaft and provided with a slightly-hooked or upwardly-curved end, a second arm secured intermediate of the ends of said shaft, an extension pivotally secured to said second arm, a projecting portion on said extension, a roller on said projecting portion, a cam secured to a suitable portion of the frame of the binder and adapted to engage said roller and to cause the extension of the arm in rotating to force the lower 95 portion or stalk end of the sheaves down the discharge-table at the same time as the other arm forces the head ends down the discharge-table, said extension being further adapted to release its pressure on the sheaf before the same is discharged whereby the sheaf will be tilted up into a substantially vertical position by the action of the arm with the lower hooked or curved end at the moment when it is being discharged from the binder as and for the purpose specified. 100
8. In combination a plurality of forks, pairs of arms supporting said forks normally in an upwardly - slanting position, a substantially vertical shaft, upper and lower rotatable collars 105 on said shaft to which said arms are pivotally secured, a roller on the upper end of the outer arm of each pair, a cam secured to the shaft and adapted to be engaged by said rollers, a semicylindrical portion extending downwardly from the lower rotatable collar, a fixed collar secured to the shaft and having an upwardly - extending semicylindrical portion thereon, ratchet-teeth formed on the upper surface of the upper rotatable collar, a ratchet- 110

- 130

disk rotatably mounted on the shaft, spring means for holding said ratchet-disk in operative engagement with the ratchet on the other rotatable collar, means for intermittently rotating said upper ratchet-disk a determined amount each time a sheaf is thrown out from the binder, and rotatable arms on the binder knotter-shaft whereby the sheaves are thrown

from the binder in a substantially vertical position as and for the purpose specified.

Signed at New Liskeard, in the Province of Ontario, this 31st day of March, 1905.

WILLIAM HUMPHREY PERRIN.
